UNITED STATES PATENT OFFICE.

RICHARD P. ELMORE, OF SULPHUR, OKLAHOMA

ATTACHMENT FOR SPECTACLES.

Application filed August 9, 1921. Serial No. 491,001.

To all whom it may concern:

Be it known that I, RICHARD P. ELMORE, a citizen of the United States, residing at Sulphur, in the county of Murray and State of Oklahoma, have invented new and useful Improvements in Attachments for Spectacles, of which the following is a specification.

This invention relates to an attachment for spectacles and has for its primary object the supporting of an auxiliary lens in place that the same may readily assume a position directly in front of the lens of the spectacle or to one side thereof.

An object of the invention is the provision of means whereby the auxiliary lens may be quickly connected to or detached from the spectacle frame and in a manner that the spectacle frame will not have to be reconstructed.

A feature of the invention is the construction and arrangement of parts whereby the auxiliary lens may be quickly thrown to a position of accurate parallelism with one of the lenses of the spectacle.

With these and other objects in view the invention will be better understood from the following detailed description taken in connection with the accompanying drawing

30 wherein:

Fig. 1 is a perspective view showing my attachment in place.

Fig. 2 is a detail sectional view.

Fig. 3 is a plan view.

35 Fig. 4 is a detail bottom plan view of the clamp.

Again referring to the drawings illustrating one of the many constructions of my invention the numeral 1 designates an ordinary frame of a spectacle having the usual 10 temple joint 2. My invention consists of a clamp 3 composed of a block 4 having a horizontal portion engaging over the joint 2 and a vertical portion 6 engaging against the 15 joint and conforming to the curvature thereof. A resilient clip 7 is connected to the block and acts against the joint 2 in a man-

ner to hold the block in tight engagement with the joint and at the same time allowing the clamp to be readily detached from the 50 joint. The block is further provided with ears 8 pivotally connected to one limb 9 of a substantially L shaped link 10. The other limb 11 of the link is formed into a head 12 pivotally connected to the ears 13 of a ring 55 14 as clearly shown at 15.

The head 12 is provided with a shoulder 16 engaging against the ears 13 when the lens 17 supported by the ring is in accurate position with relation to the lens of the 60 spectacle. This action is further facilitated by the shoulder 18 on the block 3.

From the foregoing description taken in connection with the accompanying drawing it will be apparent that I provide an attachment that may be quickly moved into place or out of place or which may be as quickly 65 completely detached from the spectacle. It will also be noted that the parts are associated to allow accurate adjustments.

70 It is, of course, to be understood that the invention may be constructed in various other manners and the parts associated in different relations and, therefore, I do not desire to be limited in any manner except as 75 set forth in the claims hereunto appended.

Having thus described my invention what I claim is:

1. An attachment for spectacles comprising a block, shaped to engage the temple 80 joint of a spectacle, a clip for detachably holding the block in place, an auxiliary lens, and a link pivotally connecting the block to the lens.

2. An attachment for spectacles comprising a block, shaped to engage the temple 85 joint of a spectacle, a clip for detachably holding the block in place, an auxiliary lens, and a link pivotally connecting the block to the lens, said link connecting the block and 90 lens in a manner to regulate the positioning of the lens.

In testimony whereof I affix my signature.

RICHARD P. ELMORE.
